GUIDO VON HORVÁTH, OF CHICAGO, ILLINOIS.

EMBROIDERY-MACHINE.

1,087,374.

Specification of Letters Patent. Patented Feb. 17, 1914.

Application filed July 17, 1912. Serial No. 709,860.

To all whom it may concern:

Be it known that I, GUIDO VON HORVÁTH, residing at Chicago, in the county of Cook, State of Illinois, and a subject of the King 5 of Hungary, have invented certain new and useful Improvements in Embroidery-Machines, of which the following is a specification.

It is the object of the present invention 10 to provide a portable machine for making embroidery stitches on cloth and similar material, the machine being under the ready control of the operator so that artistic designs and complex patterns may be executed 15 as desired.

The machine hereinafter disclosed as an embodiment of the present invention comprises a needle movable through the cloth and working in conjunction with a looper 20 located above the cloth and in position to engage the thread as the needle recedes, lifting the thread sufficiently to form a loop and otherwise controlling the motion of the thread so that successive introductions of 25 the needle through the cloth will produce a succession of loops or chain stitches lying on the face of the cloth and tracing out the design or pattern to be executed.

The special and novel phase of the embodiment here disclosed will be better understood from reference to the following detailed description which is to be taken in conjunction with the accompanying drawings, wherein—

35 Figure 1 is a perspective view somewhat diagrammatic, illustrating the machine as arranged for use. Fig. 2 is a side elevation with some parts in section, showing the machine in its initial or inactive position. Fig. 40 3 shows the machine with the looper swung back and the needle raised to bring its thread in position to be caught and held by the moving looper. Fig. 4 is a perspective view of the lever mechanism whereby 45 the necessary motions are transmitted to the looper and to the needle. Fig. 5 is a side elevation of the thread take up device. Fig. 6 is a transverse section adjacent to the looper and illustrating the operative connections for the needle and the looper mechanism. Figs. 7, 8 and 9 are details of the 50 looper in various positions, and Fig. 10 is an enlarged detail view on the line 10—10 of Fig. 6 showing the spiral spring for returning the looper after it has been swung 55 out of normal position.

As indicated in Fig. 1, the complete machine is to be used for executing embroidery patterns, as on a piece of cloth 1, which may be stretched over a suitable frame 2 60 as indicated. Fig. 1 while somewhat diagrammatic in character, indicates that the complete embroidery machine may include a supporting pedestal 3 carrying a pivotally mounted rectangular frame 4 serving as a 65 swinging support for the pivotally mounted frame 5 whereon the needle and looper are supported. A suitable operating cable 6 leads back from the frame 5 over suitable sheaves and by way of suitable bell cranks 70 to a foot lever 7 or other actuating mechanism within reach of the operator. Successive depressions of the foot lever 7 serve to project the needle through the cloth and also serve to actuate the looper whereby 75 each stitch is completed as will hereinafter be explained more in detail.

Fig. 2 shows the embroidery machine with the several operative parts in their initial position. The frame there disclosed may be 80 of metal provided at the rear corners with trunnions 8 and 9 to serve as pivotal mountings and having at its front a head section 10 which can be swung outward about a pivotal support 11 when the machine is to 85 be slipped into operative position to embrace the cloth, as shown in Fig. 1. A spring catch 12 coöoperating with a projecting raised lug 13 on the head member serves normally to hold the head in its active position, as shown in Fig. 2. Immediately below the head 10 is a work platform 14 which may be pivotally mounted at 15 to permit withdrawal of some of the other parts when desired. The needle 16 is carried in a block 95 17 mounted to slide in guideways formed in four upright guiding bars 18 on the top of which the platform 14 normally rests. The upward or forward movement of the needle is effected by means of a cross-head 19 which passes through the block 17 and is connected with a pair of pitmen 20 actuated by cross-bar 21 (Fig. 5) carried by an arm 22 (Fig. 2) projecting from a head wheel 23 mounted on a stationary horizontal shaft 24 housed in a box at the lower forward corner of the machine frame. A projecting arm 25 is secured to the head wheel and is provided with an actuating cable 26 which passes over a sheave 27 for 100 connection to operating levers as herein-after explained. A rope or cable 26 will 105 110

swing the head wheel 23 and advance the needle 16 upward through the platform 24 and through the cloth resting thereon. A spiral spring 28 housed between the guide members 18 and secured to the needle block 17 serves to retract the needle after each advance and thus constitutes an automatic returning mechanism for the needle. The needle may be held in its block 17 by means 10 of a set screw 29 (Fig. 6), or in any other suitable manner.

The looper 30 as shown in Figs. 7 to 9 inclusive, is in the nature of a strip of metal bent or cut to circular form and having its 15 front or forward end notched at 31 and rounded off at 32 so that the looper may engage the loop of thread formed at the side of the needle as shown in Fig. 7 when the needle begins its return movement through 20 the cloth, it being understood that the looper is mounted on a central axis and turns or swings at just the proper time relative to the needle movements. The looper 30 is supported solely on two projecting 25 studs 33 and 34 carried by a disk 35 which is mounted on a shaft 36 (Fig. 6) carrying a pulley wheel 37 within which is a spiral spring 61 arranged like a clock spring, see Fig. 10, having its outer end 62 secured to 30 the head section 10, and its inner end 63 secured to the pulley 37, and serving to return the looper to its initial position after it has been swung to the position shown in Fig. 7 by a pulley or actuating cable 38 which is 35 wound on the pulley wheel 37. A thread guide 39 is mounted within the looper member and is unsupported except for its engagement with the inner face of the looper and its similar engagement with a shoulder 40 projecting inward from the boxing 41 (Fig. 6) which forms a part of the looper casing or head. In other words, the thread 45 guide 39 floats within the looper member, but cannot rotate because of its frictional engagement with the part 40. A bracket 42 in the form of a resilient metal loop projects from the front face of the thread guide 39 into proximity to the presser foot 43 with which the looper head is provided. The lower 50 corner of the thread guide 39 is bent laterally and narrows down to a spring member 44 which is in position to assist in spreading out the thread loop and which is spaced apart from the bracket 42 sufficiently to admit 55 the needle when it comes upward through the cloth.

The initial position of the looper is illustrated in Fig. 9, there being a thread loop well spread out by the spring members 42, 60 44. The next operation consists in swinging the looper backward into the position shown in Fig. 7 and projecting the needle forward through the cloth and withdrawing it, as shown in Fig. 7, just sufficiently to 65 make the thread bulge out at the side of

the needle in the form of a loop directly in the path of the notch 31 of the looper. The looper is then advanced into engagement with the thread at the needle and carries the thread upward in the form of a long loop 70 encircling the thread guide 39 until the looper reaches approximately the position shown in Fig. 8, whereupon the thread drops out of the notch 31 and slips down between the thread guide and the shoulder 40 forming a large loop encircling the spring members 42 and 44 as shown in Fig. 9. The needle has meantime been drawn down through the cloth and the take up device has taken up the slack in the loop. 75

The take up device to be used in the machine may vary in its construction, but Fig. 5 illustrates one arrangement, which is suitable. That construction includes a take-up arm 45 pivotally mounted on suitable brackets and actuated by a swinging rod 46 which slides through a tubular guide-way in the arm 45 and is pivotally mounted on a projection 47 movable with the cross-head 19 of the needle block. A tension spring 48 overlaps the side of the take-up arm and is so positioned that for a downward swinging movement of the arm the spring will slide upward along the arm and so increase the grip on the thread to be pulled. The take-up device is so timed in its operation with respect to the needle movement that it does not begin to pull the thread and shorten up the loop until the needle has reached its proper relative position. Each successive 100 advance of the needle through the cloth and each corresponding forward swing of the looper forms a loop in the thread which is carried upward over the thread guide 39, and which is then shortened up through the 105 action of the take up device until it is reduced to the form of a small horizontal loop, as shown in Fig. 9, arranged to encircle the needle opening of the presser foot, with the result that the needle when it next 110 comes up through the cloth passes through the horizontal thread loop of Fig. 9 and on delivering its thread to the looper makes the chain stitch illustrated somewhat diagrammatically in Figs. 7 to 9. After each 115 movement of the needle the embroidery machine as a whole is shifted to a new position, the length of stitch being controlled by the operator and the direction of motion being made to conform with the pattern to be executed on the cloth. 120

Various agencies may be employed to effect the movement of the needle, the looper and the take up device in their proper relative sequence, but the embodiment illustrated in the drawings includes a plurality of levers, suitably connected to the needle actuating cable 26 and to the looper actuating cable 38. The lever construction includes a main lever 49 pivotally mounted on 130

the rear side of the frame and carrying a grooved segment 50 over which the looper actuating cable 38 is passed, and at the remote end of which that cable is secured. 5 The other arm of the lever is attached to a strong spiral spring 51 anchored to the side of the frame and operative to hold the main lever in the position shown in Fig. 2, but permitting upward swinging movement of 10 that lever under the action of a main operating cable 52 which passes out for connection to the cable 6 of Fig. 1, so that it may be actuated through movement of the treadle 7. The pivotal mounting of the lever 15 49 is in the form of a stationary shaft 53 whereon is loosely mounted a spur gear 54 rigidly attached to a plate having arms 55 and 56 projecting outward for engagement with a lug 57 carried at the side of the lever 20 segment 50. Meshing with pinion 54 is a second pinion 58 rigidly mounted on a transverse shaft 59 which is secured to a lever 60 connected to the needle cable 26. Initially, the several levers are in the position shown 25 in Fig. 2. A rope or cable 52 will swing lever 49 until its projecting lug 57 engages arm 56 and initiates movement in the gears 54 and 58. In the meantime the looper cable 38 has been pulled sufficiently to swing the 30 looper against the tension of its clock spring into the position shown in Fig. 3, where it is ready to receive the thread from the needle. A further movement of lever 49 will revolve the spur gears, thereby pulling upward on the needle lever 60 and forcing the needle 35 upward through the cloth to the position shown in Fig. 3. Then, on release of the main cable 52, the coiled spring 51 will turn the main lever backward and at the same 40 time the tension spring 28 located under the needle block will retract the needle simultaneously with the rotation of the looper under the action of the clock spring housed in the pulley wheel 37. 45 While I have herein disclosed one embodiment of the present invention, I am aware that changes in detail may be made without departing from the spirit thereof, and I desire that the protection here sought 50 should include such changes and modifications in detail as reasonably may be made within the terms of the appended claims.

I claim—

1. In a hand embroidery machine, the 55 combination of a looper head, a housing carried thereby, a shaft journaled within said housing, a disk carried by one end of said shaft, a looper within said housing and permanently secured in a spaced relation to 60 the outer face of said disk, a thread guide being frictionally supported by said housing and looper, said guide being held in a stationary position with respect to the housing, resilient projections carried by the 65 threaded guide, and a needle movable up-

ward into the looper between the said resilient projections for the purpose specified.

2. A hand embroidery machine comprising in combination, a movable looper head, a disk rotatably mounted within said looper head, a circular looper, a pair of studs carried by the outer face of said disk for permanently holding the looper thereto, a floating thread guide within said looper, a bracket projecting from the outer face of the thread guide and extending over the outer face of the looper, a spring member depending from the threaded guide and extending below the looper, and a needle movable upward into the loop of thread normally formed by a movement of said looper and normally held by the bracket and spring carried by the thread guide. 75

3. In a hand embroidery machine, the combination of a needle block, a guideway therefor, a pitman for moving said block, means for intermittently operating said pitman, a looper head positioned above said needle block, a looper and thread guide carried by the lower end of the looper head, 90 the looper being movable about the thread guide whereby the thread when carried upward by the operating needle will be received and held in the form of a loop until the needle makes its next succeeding upward movement through the work. 95

4. In an embroidery machine the combination of a needle carrier, pitmen for actuating said carrier, a cable operatively connected to move said pitmen when the 100 needle is to be forced through the work, a circularly movable looper, a thread guide, said looper being positioned above said needle and enveloping said thread guide, a cable for moving said looper in one direction, a spring for moving said looper in the opposite direction, levers connected respectively with said operating cables, and an operative connection between said levers to time the movements of said looper with respect to said needle. 110

5. In a hand embroidery machine, the combination of a needle block, a guideway therefor, means for operating the block, a looper head pivotally mounted above the 115 needle block and adapted to swing in a horizontal plane, a circular movable looper mounted within the lower end of the looper head, a thread guide inclosed by the looper and adapted to receive a loop formed by 120 said looper, said guide having resilient projections to hold said loop in horizontal position over the path of the ingoing needle, and means for swinging said looper forward and backward to accompany the corresponding movements of the needle. 125

6. In a hand embroidery machine, the combination of a work support, a looper head, a needle positioned for advancement through said support into said looper head, 130

a looper for engaging the thread advanced by the needle and pulling it upward into an enlarged loop, a thread guide receiving said loop, said guide having resilient projections for shifting said thread into a small horizontal loop, a take up device for pulling the enlarged loop of thread downwardly under the resilient projections, and means for swinging said looper backward into position for producing a new loop when the needle is advanced through the last thread loop carried by the thread guide.

7. In an embroidery machine, the combination of a needle, a needle block supporting said needle, a guide way for said needle block, pitmen for moving said block along said way, a head wheel for actuating said pitmen, a cable connected to actuate said head wheel, a take up device operatively connected with said needle block and operative to control the thread loop, a circularly movable looper positioned above said needle and inclosing a detached thread guide, said guide having resilient projections arranged to form a thread loop enveloping the line of movement of said needle, a cable for ac-

tuating said looper in one direction, and actuating levers associated with said looper cable and with said needle cable to time the movement of the looper with respect to the needle when the respective cables are actuated through said levers.

8. A hand embroidery machine comprising in combination a circular looper, a thread guide frictionally positioned within said looper and having resilient projections, means for holding the thread guide in a stationary position, a needle movable upward into the loop of the thread normally formed by the looper and normally held by the resilient portions of said thread guide and a single operating means operatively connected to the said needle and looper for simultaneously operating the same.

In witness whereof, I hereunto subscribe my name to this specification in the presence of two witnesses.

GUIDO VON HORVÁTH.
